UNITED STATES PATENT OFFICE.

BYRON D. HATHWAY, OF WOOLSTOCK, IOWA.

AUTOMATIC AIR-SUPPLY DEVICE.

1,175,757.

Specification of Letters Patent. Patented Mar. 14, 1916.

Application filed September 28, 1915. Serial No. 52,975.

To all whom it may concern:

Be it known that I, BYRON D. HATHWAY, a citizen of the United States, residing at Woolstock, in the county of Wright and State of Iowa, have invented certain new and useful Improvements in Automatic Air-Supply Devices, of which the following is a specification.

The invention relates to an air supply device, and more particularly to the class of automatic air supply devices for use with internal combustion engines.

The primary object of the invention is the provision of a device of this character, wherein the same can be mounted upon the intake manifold of an internal combustion engine, so that air from the atmosphere will be automatically admitted to the manifold prior to the consumption of the mixture in the cylinder of the engine, thereby increasing the power of the latter, with a minimum consumption of fuel or gas.

Another object of the invention is the provision of a device of this character, wherein the supply of air from the atmosphere can be conveniently regulated at will, thereby varying the grade of the mixture, as the occasion may require.

A further object of the invention is the provision of a device of this character, wherein the necessity of any change in the intake manifold of the engine is obviated, and a quantity of air from the atmosphere will be automatically admitted thereby for assuring maximum power.

A still further object of the invention is the provision of a device of this character wherein the construction thereof is novel in form, possessing few parts, thereby assuring accuracy and the perfect working of the same, while the engine is active.

A still further object of the invention is the provision of a device of this character, which is extremely simple in construction, thoroughly reliable and efficient in operation, strong, durable, automatic in action, and inexpensive in manufacture.

With these and other objects in view, the invention consists in the features of construction, combination and arrangement of parts as will be hereinafter fully described, illustrated in the accompanying drawing, and pointed out in the claim hereunto appended.

In the accompanying drawing: Figure 1, is a fragmentary side elevation of an in-

ternal combustion engine, showing the device constructed in accordance with the invention applied. Fig. 2, is an enlarged vertical sectional view through the device. 60

Similar reference characters indicate corresponding parts throughout the several views in the drawing.

Referring to the drawing in detail, A, designates a portion of the ordinary intake 65 manifold, of the usual internal combustion engine, while B, designates the automatic air supply device, hereinafter fully described.

The air supply device B, comprises a cylinder 5, formed with a rounded top 6, having therein a central air inlet port 7, provided concentrically thereof with a valve seat 8, in which is normally engaged a ball valve 9, for closing the same. The cylinder 5 is preferably of uniform diameter 70 throughout its length, and is threaded at its lower end onto a bottom cap 10, having communication centrally thereof with an elbow 11, integrally formed therewith and terminating in a nipple 12, adapted to be 75 detachably tapped into the intake manifold A, leading to the cylinders of the engine.

Arranged interiorly of the cylinder 5, is a coiled expansion spring 13, one end of which has its bearing upon the cap 10, while 80 the other end supports the ball valve 9, so as to normally hold the same engaged in the seat 8, therefor, and thereby cut off the supply of air to the cylinders of the engine on the compression strokes of its pistons. 90

Provided in the elbow 11, is a plug valve 14, which is actuated by hand so that the device can be cut off from the engine, or the quantity of air supply from the atmosphere can be regulated at will. 95

In the operation of the device when the engine is active and upon the suction stroke of the piston in each cylinder the ball valve 9, is unseated thereby opening the port 7, and the atmospheric air is drawn into the manifold and delivered to the cylinder of the engine with the mixture for increasing the power of the said engine, and thus minimizing the consumption of fuel for the running of the engine. The ball valve 9, will eliminate the possibility of the accumulation of dirt, dust or foreign matter thereon or upon the seat, so that the said ball valve will become positively seated under the action of the spring 13, supporting the same. The 100 cap 10, is of uniform cross sectional diameter, and is formed with external threads 110

15, throughout its length, so that the threaded end of the cylinder 5, can be readily adjusted, so as to vary the tension of the spring 13 interiorly thereof. Engaged on the cap 10, is an adjustable lock nut 16, which works against the threaded end of the cylinder 5, to secure the same in its adjusted position upon the cap, and thereby prevent the accidental turning of 10 the cylinder upon the latter.

From the foregoing it is thought that the construction and manner of operation of the device will be clearly understood, and therefore a more extended explanation has been 15 omitted.

What is claimed is:—

An air supply device of the character described, comprising an elbow having an air passage therethrough, and also having a 20 plug valve shell formed in one branch thereof, a rotatable plug valve mounted in

the shell and having an aperture for registration with the passage in the elbow, an externally threaded enlarged terminal formed on one end of the elbow, a lock nut 25 adjustably engaged with the threaded terminal, a cylinder adjustably engaged on the threaded terminal and acted upon by the nut to lock said cylinder, a rounded outer end on the cylinder and having an inwardly tapered walled aperture centrally thereof, the inner end of the wall of the aperture forming a valve seat, a ball valve interiorly of the cylinder and engaged with the seat, and a coiled expansion spring within the 30 cylinder and working against the enlarged terminal and ball valve to normally hold the latter against the seat.

In testimony whereof I affix my signature.

BYRON D. HATHWAY.
